Primary Examiner—Cathron C Brooks*Assistant Examiner*—Austin Murphy(74) *Attorney, Agent, or Firm*—Edgar A. Zarins; Nirav D. Parikh(57) **CLAIM**

The ornamental design for a cube shelf, as shown and described.

DESCRIPTION

FIG. 1 is a perspective view of a cube shelf showing our new design;

FIG. 2 is a front elevational view thereof;

FIG. 3 is a right side view thereof, the opposite side being a mirror image of the side shown;

FIG. 4 is a perspective view of a second embodiment thereof; and,

FIG. 5 is a perspective view of a third embodiment thereof.
